UNITED STATES PATENT OFFICE.

CHARLES W. NELSON, OF CHICAGO, ILLINOIS, ASSIGNOR TO TABLET & TICKET COMPANY, OF CHICAGO, ILLINOIS, A CORPORATION OF ILLINOIS.

BULLETIN BOARD.

Application filed April 16, 1927. Serial No. 184,195.

This invention relates to improvements in directory or bulletin boards, and more particularly to boards having interchangeable name strips or plates thereon, and has as its 5 principal object to provide manually operated indicator means in connection with such name plates to show the presence or absence of the persons named on said directory or bulletin board.

10 The invention may best be understood by reference to the accompanying drawing, in which

15 Figure 1 is a face view of a bulletin board constructed in accordance with my invention.

Figure 2 is a side view of the board shown in Figure 1 with parts broken away to show the construction of the name plates and retaining grooves therefor.

20 Figure 3 is a view in perspective of the name strip and indicator forming the principal part of my invention.

Figure 4 is an enlarged sectional view taken on line 4—4 of Figure 3.

25 Referring to the embodiment of my invention shown in the drawings, the same is shown as applied to a directory board 10 having horizontally disposed grooves 11 formed in the face thereof and adapted to receive removable indicia bearing strips having inturned tongues fitting in said grooves, so that the strips are held flat against the face of the board.

30 In the form shown herein, the face of the board is covered with felt cloth 12 which also extends into the grooves 11—11 so as to assist in holding the tongues of the indicia in the usual manner.

35 In carrying out my invention, I provide a plurality of name strips 15—15 consisting of a base 16 of relatively stiff material, such as metal, and provided with a tongue 17 arranged substantially at right angles to and projecting from the rear of said strip to form the holding member therefor when inserted in the grooves of the board 10. In the form shown, the name strip is of the inverted-L type, in which the tongue 17 projects from the upper edge of the flat name plate or base 16, although other forms of tongue may also be used, if desired. The tongue 17 extends along the central portion of each base 16 but terminates at a distance from one end thereof, as for instance, the left end, as clearly shown in the drawings.

An indicator 19 is mounted on the end of the base 16 so as to slide freely thereon, said indicator preferably consisting of a metallic band or strip 20 having its upper and lower edges extending around the base and having a depressed or upset portion 21 on its face thereof so as to be readily manipulated by the fingers. A portion at the left end of the base is preferably bent or upset inwardly, as indicated at 22, so as to retain the indicator 19 permanently on the base. The arrangement is such that the indicator may slide freely from the position at the extreme left end of the base where it is limited by the upset portion 22, to a second position 70 toward the center of the base, where its movement is stopped by engagement with the tongue 17.

The face of the strip forming the base 16 is adapted to receive the various letters, such as those used in the names to appear on the directory, such letters being usually applied by means of glue or the like, but with the name spaced to the right of the left end of the tongue, so as to permit the indicator 19 80 to slide freely between said tongue and the extreme left end of the strip.

In a completed directory, the strips above described are utilized in the following manner: A series of strips each carrying names of parties to be included in the directory, are mounted on the bulletin board with their tongues extending in the grooves 11—11 in the usual manner. A smaller or shorter strip 25 is mounted near the upper edge of the board over the ends of the strips carrying the indicators 19 and has the words "In" and "Out" thereon arranged in two columns corresponding to the two extreme positions of the indicators when they are moved to the right or left positions. Manipulation of each indicator, therefore, will show whether the party represented on its respective strip is in or out, as the case may be.

100 Each of the name strips with its indicator is handled as a unit for addition or substitution of various names, and when in place on the board, each of the sliding indicators 19 may be pressed into close contact with the 105 felt cloth of the board so that they are frictionally held from displacement in either of their two permissible positions.

110 While I have illustrated and described the particular embodiment of my invention,

2
it will be understood that I do not wish to be limited to the exact construction shown and described, but that various changes and modifications may be made without departing from the spirit and scope of my invention.

I claim as my invention:

1. In a device of the character described, a name strip consisting of a base, an indicator slidably mounted on one end of said base, a longitudinally disposed tongue projecting from the rear of said base for insertion in a grooved display board, said tongue terminating at a predetermined distance from the end of said base carrying said indicator, and forming a stop for the latter in one position of adjustment thereof, and an upset portion on the end of said base carrying said indicator and forming a stop

for the latter in a second position thereof. 20

2. In a device of the character described, a name strip consisting of a base, an indicator slidably mounted on one end of said base, a longitudinally disposed tongue integral with and bent rearwardly from one margin of said base for insertion in a grooved display board, said tongue terminating at a predetermined distance from the end of said base carrying said indicator and forming a stop for the latter in one 30 position of adjustment thereof, and an inwardly bent projection formed on the end of said base carrying said indicator and forming a stop for the latter in a second position thereof. 35

Signed at Chicago this 13th day of April, 1927.

CHARLES W. NELSON.
